INVENTOR

Horace T. Fleisher

BY

Frank D. Bussan

ATTORNEY.

UNITED STATES PATENT OFFICE.

HORACE T. FLEISHER, OF ELMINS PARK, PENNSYLVANIA, ASSIGNOR TO NOTASEME HOSIERY COMPANY, OF PHILADELPHIA, PENNSYLVANIA, A CORPORATION OF PENNSYLVANIA.

DOLL.

1,358,069.

Specification of Letters Patent. Patented Nov. 9, 1920.

Application filed August 6, 1919. Serial No. 315,602.

To all whom it may concern:

Be it known that I, HORACE T. FLEISHER, a citizen of the United States, residing at Elkins Park, county of Montgomery, and Elkins Park, State of Pennsylvania, have invented a new and useful Improvement in Dolls, of which the following is a full, clear, and exact description, reference being had to the accompanying drawings, which form a part of this specification.

The object of my invention is to provide a child's doll which will be both attractive in appearance and durable, and which may be inexpensively constructed of waste materials.

Referring to the accompanying drawings in which I have illustrated a preferred embodiment of my invention and in which like symbols refer to like parts in the various figures,—

Figure 1 is a front elevation of the complete doll.

Fig. 2 is a front elevation of the body, legs, head and cap forming section.

Fig. 3 is a front elevation of the arms and means for attaching them to the body.

Fig. 4 is a front elevation of the final covering or garment.

The body portion *a* is formed from an im-
30 perfect section of knitted fabric, made by
hosier manufacturers, as ribbed tops for
stockings. The lower end of the fabric is
split with the wales and sewed to form legs
b, *b*. Near the upper end the fabric is gath-
35 ered in and tied, leaving a free end which is
folded on dotted lines *c* to form a cap *d*.

A face *e* is painted, or otherwise drawn
on the fabric, and the body portion and legs
40 are stuffed with cotton waste. The legs may be
tied in at the angles as at *f* to form feet.

The arms *g* are formed in another section
45 of the same fabric, cut out and sewed to form
the arms and a body section *h*. The wales
of the fabric in the arm section run with the
arms, since the rib tops are long in the di-
rection of the wales, but relatively narrow
across them. The arms may be tied in at
the wrists as at *i* to form hands.

A garment for the doll is formed from a
50 third section of rib top and has a body por-
tion *j*, in which are cut arm-holes *k*. The
upper part of the section is adapted to be
folded on dotted lines *l* to form a collar,
while the lower part is split, in the direc-
tion of the wales, and sewed to form pants

legs *m*. The body of the garment section is
adapted to be folded on dotted lines *n*, when
on the doll to give the effect of a jersey
and pants as shown in Fig. 1.

In assembling the doll, the body section *h* 60
is passed over the doll's head and about its
body, thus securing the arms in place.
The garment is passed over the head and
about the body, the legs being put through
the pants. The collar and cap are formed 65
by folding on lines *l* and *c* respectively and
the body portion *j* of the garment is folded
on lines *n* to give the jersey and pants effect.

Having now fully described my invention, what I claim and desire to protect by 70
Letters Patent is:—

1. A doll comprising a knitted section
forming a head, a body and legs, and an
other knitted section forming arms and an
element surrounding the body, the arms be- 75
ing maintained in position on the body by
means of said element.

2. A doll comprising a knitted section
forming a head, a body and legs, another
knitted section forming arms and an element 80
surrounding the body, and a third knitted
section forming a garment slipped over the
body-surrounding element of the second
knitted section.

3. A doll comprising a knitted fabric 85
forming legs, body, head and extending be-
yond the head, the fabric being constricted
at the junction between the head and said
extension, said extension being folded down
90 over the upper part of the head and also
folded upon itself on circumferential lines
to form a rimmed cap.

4. A doll comprising a knitted section
forming a head, a body and legs and ex- 95
tending beyond the head, the fabric being
contracted at the junction between the head
and said extension, said extension being
folded to form a cap covering the top of the
head, another knitted section forming arms
100 and an element surrounding the body, and
a third knitted section forming a garment
slipped over the second knitted body-sur-
rounding element.

5. A doll comprising a knitted section
forming a stuffed head, body and legs and 105
extending beyond the head, and a second
knitted section slipped over the first section
and foldable to give the effect of jersey and
pants.

6. A doll comprising a stuffed knitted 110

section forming a head, a body and legs, a second knitted section forming a body-engaging element and arms, and a knitted garment section fitting over the body and the second knitted section and foldable to give the effect of jersey and pants.

7. A doll comprising a knitted section forming a stuffed head, body and legs and extending beyond the head, a second knitted section forming a body-engaging element and arms, and a one-piece garment on the body foldable at the waist to give the effect of a jersey and pants, the extended end of the first section being foldable to form a

15 cap.

8. A doll formed of waste or imperfect fabric produced in hosiery manufacture and comprising the following elements: a

knit tubular fabric split at one end, each split section being closed to form legs, the 20 tube at the other end being constricted to form a foldable cap; all except the cap portion being stuffed to form a head, a body and the legs; a second knit fabric having a central tubular portion adapted to be 25 slipped over the body and closed end tubular portions stuffed to form the arms; and a third tubular section split at one end, each split section being secured along the side to form pants, the main body of the tubular 30 section being slipped over the body and foldable to give the effect of a jersey.

In testimony of which invention, I have hereunto set my hand, at Philadelphia, Pa., on this 4th day of August, 1919.

HORACE T. FLEISHER.
